SIGNAL OPERATING MECHANISM

Filed June 30, 1931

INVENTOR.
Clarence C. Raymond.

BY *Thos. Donnelly*
ATTORNEY.

UNITED STATES PATENT OFFICE

CLARENCE C. RAYMOND, OF DETROIT, MICHIGAN

SIGNAL OPERATING MECHANISM

Application filed June 30, 1931. Serial No. 547,939.

My invention relates to a new and useful improvement in a signal operating mechanism adapted for use primarily on vehicles of the automotive type and intended to operate so that when the vehicle is traveling beyond a predetermined speed the mechanism will be actuated to one stage for operating a display member and when the speed is lowered to a predetermined rate, the mechanism 10 will be actuated for operating another display member.

It is an object of the present invention to provide a device of this class which will be simple in structure, economical to manufacture, durable, and highly efficient in use.

Another object of the invention is the provision of a rotating shaft, the speed of rotation of which will be dependent upon the speed of operation of the vehicle and the provision of this shaft with mechanism, the operation of which will be dependent upon the rotation of the shaft with which associated.

Another object of the invention is the provision of a rotating shaft having an axially movable switch operating mechanism mounted thereon and provided with mechanism for axially moving the same upon the rotation of the shaft at predetermined speeds.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a central sectional view of the actuating mechanism showing it applied.

Fig. 2 is a view taken on line 2—2 of Fig. 1.

Fig. 3 is a diagrammatic view of the wiring used in the invention.

Fig. 4 is a view taken on line 4—4 of Fig. 1.

Fig. 5 is a sectional view through a light 45 housing used in the invention.

While in the drawing I have illustrated the invention used with lights which are electrically operated and serve to function as signals, it will appear obvious as the description proceeds that an electric alarm could be

used in the invention as well as the lights without in any manner interfering with the operation of the controlling mechanism.

In the drawing I have illustrated a lamp housing 9 having a transparent closure 10 at one side from which the rays of light from the lamp 11 which is positioned within the housing may shine. In the adaptation of the invention as illustrated, I use a pair of these lights 11 and 13, these lights being grounded 60 at 12 and 14 respectively. The light 11 is connected by the wire 15 to the resilient contact arm 16 which is mounted in the switch housing 57. The light 13 is connected by the wiring 17 to the resilient switch or contact arm 18 which is also mounted in the switch housing 57. These arms 16 and 18 are adapted to engage the contact member 19 which is mounted in the switch housing 57 and which is connected by the wire 20 to one side 70 of the battery 21, the opposite side of which is grounded as at 22.

In the drawing I have illustrated the invention used in connection with an automobile engine shaft 23 which projects rearwardly to the universal housing 24 and which is enclosed by the casing 26. Fixedly mounted on this drive shaft 23 is a worm wheel 25 meshing with which is the worm 27 fixedly mounted on the shaft 28. This shaft 28 projects into the gearing housing 29. Fixedly mounted on the shaft 28 within the gear housing 29 is a gear 30 meshing with a gear 31 which is fixedly mounted on the shaft 32. The shaft 28 and its connections is the usual 85 one for driving the flexible shaft of the speedometer used on a vehicle. Connecting to the shaft 32 is a flexible shaft 33 enclosed by the sheathing 34. This shaft 33 is connected to the shaft 35 which projects into the housing 90 36 and is journaled in the bushing 37. The gland 38 engages the flange 39 of the flexible sheathing 34 and serves to retain the shaft 33 in connected relation to the shaft 35.

Fixedly mounted on the shaft 35 within the 95 housing 36 is a collar 40 provided with a plurality of pairs of radiating lugs 41 and 42 which are in spaced relation to each other. Pivotally mounted at one end between the pairs of lugs is an operating arm 43 which is 100

bifurcated at its pivoted end to provide a space 44 in which engages one end of the link 44' which is pivoted to the arm 43. The opposite end of the link 44' is pivoted between 5 a pair of lugs 45 which extend outwardly from a collar 46 which is slidably positioned on the shaft 35. A neck 47 projects from the collar 46 and positioned about this neck 47 is a bearing comprising the ball retainers 48 10 and the balls 49. A cup shaped housing 50 is pressed upon the outer ball retainer 48. Pivottally connected at their ends to the cup shaped housing 50 are the yoke arms 51 and 52 which extend from the tree of the yoke 53 15 which is pivotally mounted between the lugs 54 which are positioned within the housing 36. The arm 53 projects through a slot 58 formed in the housing 36 and the free end of the tree or arm 53 is provided with a roller 20 55 which is adapted to engage the spring contacts or switch arms 16 and 18. A weight 56 is fixedly mounted on the free end of each of the arms 43.

In operation, when the shaft 23 is rotated, 25 the shaft 35 will rotate. As the shaft 35 rotates at a low speed, the arms 43 will through the action of the weights 56 hang downwardly so that the arm or tree 53 will be tilted to maintain the spring contact or switch arm 30 16 out of engagement with the contact 19 and thus the circuit to the light 13 will be closed.

As the speed of rotation of the shaft 35 continues, centrifugal force will move the arms 43 to approach horizontal position and 35 thus the collar 46 will be slid upwardly to rock the arm or tree 53 and move the spring contact or switch arm 18 out of engagement with the contact 19 and permit the engagement of the spring contact or switch arm 16 40 with the contact 19, thus closing the circuit to the light 11.

In this adaptation of the invention, it is my intention that the light 13 shall be a red light 45 which will be lit while the vehicle is traveling at a slow speed, thus warning the drivers of following vehicles so as to prevent a collision. It is intended that the light bulb 11 shall be a green light thus indicating when a pre-determined speed of travel has been reached 50 so that travelers of following vehicles may follow closely at a high rate of speed. While the invention is adapted for use on vehicles of all types, it is particularly adapted for use on that class of vehicles which employ a "free 55 wheeling mechanism" in which no mechanism would be operated to sound a warning or light when the feeding of fuel to the engine was stopped.

The device may be very easily and quickly 60 assembled and the durability and simplicity of the structure is believed obvious.

While I have illustrated and described the preferred form of construction of my invention, I do not wish to limit myself to the 65 precise details of structure shown, but desire

to avail myself of such variations and modifications as may come within the scope of the appended claims.

Having thus described my invention, what I claim as new and desire to secure by Letters Patent is:

1. A device of the class described, comprising: a rotatable shaft; a collar axially movable on said shaft; a switch operating arm pivoted intermediate its ends and connected at one end to said collar; a pair of switch blades engageable with the free end of said arm, the rocking of said arm in one direction moving one of said blades to open position, and the rocking of said arm in the opposite direction moving the other of said blades to open position. 75

2. A device of the class described, comprising: a rotatable shaft; a collar axially movable on said shaft; a switch operating arm pivoted intermediate its ends and connected at one end to said collar; a pair of switch blades engageable with the free end of said arm, the rocking of said arm in one direction moving one of said blades to open position, and the rocking of said arm in the opposite direction moving the other of said blades to open position; and means operable dependent upon the speed of rotation of said shaft for 80 rocking said arm to said positions. 85

3. A device of the class described, comprising: a rotatable shaft; means for rotating said shaft; a collar slidably mounted on said shaft; an arm pivotally mounted intermediate its ends and connected at one end to said collar; means operable dependent upon the speed of rotation of said shaft for moving said collar axially of said shaft and effecting a rocking of said arm on its pivot; and a pair of switch blades each engageable with the free end of said arm, the rocking of said arm in opposite directions moving said switch blades alternately to open position. 90 100

4. A device of the class described, comprising: a rotatable shaft; means for rotating said shaft; a collar axially movable on said shaft; a pair of spaced resilient switch arms normally in switch closing position; an arm pivotally mounted intermediate its ends and pivotally connected at one end to said collar and engaging at its free end between said switch arms for effecting, upon rocking, the movement of said switch arms individually to open position dependent upon the direction of rocking; a collar fixedly mounted on said shaft; swingably mounted arms carried by said fixedly mounted collar; a weight on the free end of each of said swingably mounted arms; and a link connecting said swingably mounted arms intermediate their ends to said movable collar. 110 115 120

5. A device of the class described comprising: a rotatable shaft; means for rotating said shaft; a collar slidably mounted on said shaft; an arm pivotally mounted inter- 125 130

mediate its ends and connected at one end to said collar; means operable dependent upon the speed of rotation of said shaft for moving said collar axially of said shaft and effecting a rocking of said arm on its pivot; a stationary contact member; a pair of independent, resilient contact arms, each fixedly mounted at one end and adapted for engaging at their opposite ends on opposite sides of said contact member, the free end of said pivotally mounted arm engaging between said resilient contact arms and adapted upon rocking in opposite directions for moving said contact arms alternately out of engagement with said contact member.

In testimony whereof I have signed the foregoing specification.

CLARENCE C. RAYMOND.
